UNITED STATES PATENT OFFICE

2,089,248

CARBURETOR

Robert F. Bracke, Chicago, Ill.

Application August 28, 1935, Serial No. 38,238

10 Claims. (Cl. 261—72)

My invention pertains to carburetors, and is particularly concerned with the provision of a fuel lift carburetor for the internal combustion engines of automobiles or other automotive vehicles.

In automobiles the engine is usually mounted at the forward end of the vehicle, while the fuel tank is located at the rear of the vehicle and below the engine carburetor. The head through which the carburetor must lift its fuel varies with the variation of the quantity of fuel in the fuel tank and also varies with the gradient of the road over which the vehicle is traveling. In fuel lift carburetors heretofore used it has been customary to maintain at all times sufficient suction in the float bowl of the carburetor to lift the fuel from the fuel tank to the float bowl through the maximum head which will exist under any conditions of operation of the vehicle. This means that during most of the period of vehicle operation an unnecessarily high suction is maintained in the carburetor float bowl and this decreases the efficiency of operation of the carburetor.

An object of my invention is to provide a carburetor wherein the float bowl suction varies with the head through which the fuel must be lifted so that the suction in the float bowl is sufficient only to overcome the head existing at any given time.

Another object of my invention is to improve the efficiency of fuel lift carburetors.

Another object is to maintain a constant ratio between the nozzle suction and the float bowl suction.

Another object is to provide a carburetor which provides greater engine power under most operating conditions.

Other objects and advantages will become apparent as the description proceeds.

My present invention is an improvement over the subject-matter of my co-pending application, Serial No. 6,421, filed February 14, 1935.

In the accompanying drawing:

Figure 1 is a vertical section through a carburetor embodying my invention, the connection between the carburetor and the fuel tank being diagrammatically indicated; and

Figure 2 is a sectional view of a detail, being taken on the line 2—2 of Figure 1.

Referring to the drawing, I have shown a down draft type of fuel lift carburetor wherein the upper casting A and the lower casting B are secured together by any suitable means and together compose the main body of the carburetor.

The particular means for securing the castings A and B together are illustrated as bolts 10, and a suitable washer or gasket 12 is clamped between the castings A and B to form an air-tight seal therebetween.

The upper casting A has an air horn 14 which is shown as communicating directly with atmosphere, but which may be connected to a suitable air filter and silencer of the type now commonly used on automobile engines. In the air horn 14 is a hub 16 supported by spokes 18. The hub 16 has a vertical opening therethrough in which a Venturi tube or nozzle 20 is suitably affixed. The nozzle 20 has a primary air inlet 22 converging toward a throat 24 terminating at a step 26. Immediately beneath the step 26 are the inner ends of diagonal fuel feed passages 28 which establish communication between the interior of the nozzle and an annular chamber 30 surrounding the adjacent portion of the nozzle.

Part of the air entering the air horn 14 passes into the inlet 22 of the nozzle and mixes with fuel supplied through the diagonal passages 28. The mixture thus formed flows through the flaring portion 32 of the nozzle and strikes the flat surface 34 provided by a secondary air valve 36 mounted for reciprocating movement on the lower end of the nozzle 20. After the mixture strikes the surface 34 it flows radially and thence into the mixing chamber 38. When the engine is operating at normal speed the secondary air valve 36 is drawn down below the position shown in the drawing and secondary air flows into the mixing chamber 38 between the air valve 36 and its cooperating throat 40. From the mixing chamber 38 the combustible mixture flows through suitable passages into the upper end of the throttle bore 42 and thence into the intake manifold 44 to which the carburetor is attached by bolts 46.

A throttle valve 48 is located in the throttle bore 42 and is mounted on a pivoted shaft 50 attached to a lever 52 which is connected with the usual accelerator pedal and hand throttle of the automobile. The idle position of the throttle valve 48 is controlled by an adjusting screw 54 which contacts with a lug 56, and the full throttle position of the valve 48 is similarly determined by the engagement of a stop 58 with the lug 56.

My carburetor includes a float bowl 60 containing a float 62 which closes a gravity opened valve 64 when the float bowl 60 is full of fuel. The valve 64 controls communication between the float bowl 60 and the fuel tank 66 which is ordi-

narily located at the rear of the vehicle and below the carburetor. The fuel is sucked from the tank 66 by means which will now be described.

Part of the air entering the air horn 14 passes 5 into the upper end of a passage 68 and thence through the opening 70 in choke plate 72 and into the chamber 74 formed by a cap 76 attached to the casting B by means of the spring plate 78 and screw 80. From the chamber 74 the air passes 10 through a second opening 82 in the choke plate 72 and into a booster nozzle 84 which discharges into a bore 86. The bore 86 communicates with the upper end of the throttle bore 42 through an orifice 88 whose effective size is controlled 15 by the tapered metering pin 90 which is movable with the secondary air valve 36. The throat of the booster 84 is connected by way of small passages 92 and ducts 94 and 96 with the upper end of the float bowl 60, so that the suction created 20 in the throat of the booster 84 is communicated to the float bowl and draws thereinto fuel from the main tank 66 when the valve 64 is open.

The fuel for the primary nozzle 22 is supplied thereto from the float bowl 60 through an accelerator pump comprising a cylinder 98 in which is located a piston 100. The fuel enters the lower end of the cylinder 98 and passes upwardly through ports 102 in the piston. When the engine is idling the valve 104 is in the position 30 shown in the drawing and the fuel for the engine is supplied through the small port 106 located therein, but when the engine requires more fuel this valve 104 is raised from its seat and additional fuel flows around the outside edge of this 35 valve.

The fuel flowing past the valve 104 passes upwardly through an orifice 108 whose effective area is controlled by a pin 110 carried by the piston 100. The portion of the pin 110 which is located 40 in the orifice 108 is gradually tapered from one end to the other, so that when the piston is in the lower position shown in the drawing, the orifice 108 contains a maximum restriction and the effective area of this orifice gradually increases as 45 the piston 100 is raised. The fuel passing through the orifice 108 reaches the diagonal passages 28 and annular chamber 30 by way of the bore 112.

The piston 100 is raised by a piston rod 114 50 resting upon an adjustable screw 116 carried by one arm of a lever 118 which is pivoted to the casting B at 120. The other arm of the lever 118 is connected to the throttle control lever 52 by a link 122, so that as the throttle valve 48 is 55 opened the piston 100 is raised.

When the throttle valve 48 is suddenly opened through a wide range of movement, the additional quantity of fuel supplied to the nozzle 20 by the piston 100 would be too great if means 60 were not provided for permitting some of the fuel above this piston to bypass the piston and flow back into the float bowl of the carburetor. Accordingly, I provide a second series of passages 124 in the piston 100, these passages being nor- 65 mally closed by a spring pressed valve 126 so that when the piston is suddenly moved upward through a long stroke, part of the fuel ahead of the piston can flow through the passages 124 and past the valve 126 and thence back to the float bowl 60. The piston 100 merely rests upon the upper end of the rod 114 and is returned by a spring 128.

It is important that no air leak into the float bowl 60 around the piston rod 114. Accordingly, 70 I provide an annular space 130 intermediate the

guide for this piston rod and connect this space by way of a duct 132 with that part of the throttle bore which is below the throttle valve 48, so that any air seeping along the piston rod 114 will be drawn into the intake manifold and will not reach 5 the float bowl of the carburetor. It is to be understood that the screw 116 may be adjusted to regulate the idle position of the metering pin 110.

My invention particularly relates to the method of controlling the suction existing in the float bowl of the carburetor. This suction is created by the booster 84 and I control the degree of suction created by this booster by means of the pin 90 associated with the secondary air valve 36. The positions of the secondary air valve 36 and control pin 90 are in turn regulated by the suction created in a chamber 134 formed therebelow by the downwardly extending cup 136 of the air valve casting and the upwardly extending guide 138.

The secondary air valve 36 and control pin 90 are urged upwardly by a spring 140 which exerts its force upon a plate 142 located beneath the enlarged head of the control pin 90. The secondary air valve and control pin are drawn downwardly against the tension of this spring by the suction created in the chamber 134 through the orifice 144 and passage 146 (Figure 2) which connect this chamber with the upper end of the throttle bore 42. The suction in the upper end of the throttle bore 42 is dependent upon the position of the throttle valve 48 and the conditions under which the engine is operating.

I provide special means for varying the degree of suction in the chamber 134 independently of the suction existing in the upper end of the throttle bore 42. According to my invention the degree of suction existing in the chamber 134 is varied in accordance with the variations in head through which the fuel must be lifted from the 40 tank 66 to the float bowl 60 of the carburetor. This means that the positions of the secondary air valve 36 and of the control pin 90 are similarly varied with the variations of the fuel lift head, so that the suction maintained in the float bowl 45 by the booster 84 likewise varies with this head.

Fuel from the main tank 66 is drawn to the carburetor through a pipe 148 which connects with a chamber 150 formed in a part of the casting B. One side of the chamber 150 is closed by a flexible diaphragm 152 which is secured in place by a cap 154 which is bolted or otherwise suitably attached to the casting B. The diaphragm 152 may be made of any suitable material but is preferably composed of the same material which is used in the fuel pumps now commonly associated with automobile engines for supplying fuel thereto. The upper end of the chamber 150 connects with the float bowl inlet valve 64 by way of bores 156 and 158.

The diaphragm 152 is urged to the left by a spring 160 which is confined between one wall of the chamber 150 and a metal cup 162 which rests against the diaphragm 152. The diaphragm is moved to the right in opposition to the spring 160 by the suction created in the chamber 150 to overcome the difference in elevation between the inlet valve 64 and the upper surface of the fuel in the tank 66. This difference in level or fuel lift head varies with the amount of fuel in the tank 66 and also varies with the gradient of the road over which the vehicle is traveling at any particular instant.

The position of the diaphragm 152 thus varies 75

with the fuel lift head and controls a metering pin 164 which is lightly pressed against the left-hand side of the diaphragm by a spring 166 resting upon a sleeve 168 adjustably secured, as, for example, by threads in the cap 154. The pin 164 has a reduced and tapered left-hand end which variably controls an orifice 170 which connects atmosphere with a pipe 172 communicating through ducts 174 and 176 with the chamber 134 located beneath the secondary air valve.

When the fuel tank 66 is full and the automobile is traveling down hill, little suction is required to lift fuel from the tank 66 to the float bowl of the carburetor. Under these conditions only a small amount of suction is maintained in the chamber 150 and the metering pin 164 almost closes the orifice 170, so that the suction maintained in the chamber 134 beneath the secondary air valve is approximately equal to the suction existing in the upper end of the throttle bore 42. The secondary air valve 36 and metering pin 90 are accordingly drawn downwardly against the tension of the spring 140 and the outlet of the booster 84 is restricted so that it creates only a small amount of suction in the float bowl 60. On the other hand, when the fuel tank 66 is nearly empty and the vehicle is traveling up hill, maximum suction is required in the float bowl 60 to draw fuel from the tank 66. Under these conditions maximum suction is maintained in the chamber 150 and the diaphragm 152 is drawn inwardly against the spring 160. The light spring 166 moves the metering pin 164 to the right and allows air to enter through the orifice 170 and flow into the chamber 134 beneath the secondary air valve which assumes a higher position, thereby maintaining a greater suction in mixing chamber 38 and in the upper end of throttle bore 42. This greater suction causes booster 84 to create maximum suction in float bowl 60 and also increases the fuel lifting capacity of nozzle 20.

It is not to be understood that the degree of suction existing in the float bowl 60 alternates rapidly between the maximum and minimum. Under ordinary operating conditions the suction in this float bowl changes slowly as the fuel in the tank 66 is consumed and changes more rapidly with changes in the gradient of the road over which the vehicle is traveling. The parts are preferably so proportioned that even when the minimum degree of suction is present in the float bowl 60 a small amount of air is admitted through the orifice 170. It is to be further understood that the degree of suction maintained in the float bowl 60 is always slightly greater than that necessary to overcome the then existing fuel lift head. The metering pin 164 is preferably made adjustable. In the form shown a screw driver may be inserted through the opening 178 in the cap 154 and engaged with teeth 180 suitably provided on an enlargement of the sleeve 168 to rotate the same to any desired adjusted position. The sleeve 168 may be locked in the adjusted position by a screw 182.

The primary nozzle 22 must overcome the suction existing in the float bowl 60 in order to draw fuel therefrom. In the normal operation of my carburetor the degree of suction existing in the float bowl is less than the maximum and, therefore, my carburetor operates more efficiently and provides greater power except under the unusual condition where the fuel in the tank 66 is low and the automobile is climbing a maximum grade. Under this one unusual condition my carburetor

is just as efficient as the fuel lift carburetors heretofore known and under all other conditions it is superior to such carburetors.

While I have illustrated and described only one embodiment of my invention, it is to be understood that my invention is not limited to the precise details shown and described but may assume various forms, and that the scope of my invention is to be limited solely by the following claims.

I claim:

1. In a fuel lift carburetor of the class described, the combination of a nozzle, a float bowl for supplying fuel thereto, said nozzle having a primary air inlet, a mixing chamber into which said nozzle discharges, a secondary air valve for regulating the supply of secondary air to said mixing chamber, a booster for creating suction in said float bowl, means controlled by said secondary air valve for regulating the degree of suction produced by said booster, a source of fuel supply for said float bowl located at variable levels with respect to said bowl whereby the head through which the fuel must be lifted varies, mechanism for regulating said secondary air valve in accordance with variations in said head, and means for adjusting said mechanism.

2. A fuel lift carburetor for automobiles having a main fuel tank spaced from the carburetor whereby the difference in head between the carburetor and the surface of the fuel in the fuel tank varies, comprising a nozzle, a chamber from which said nozzle is supplied with fuel, a booster for creating suction in said chamber, conduit means connecting said chamber with said fuel tank, said means including a part movable in response to variations in said head, and means controlled by said part for regulating the suction created by said booster.

3. A fuel lift carburetor comprising a nozzle, a float bowl from which said nozzle is supplied with fuel, a tank from which said float bowl receives its fuel, the upper surface of the fuel in said tank varying in elevation with respect to said float bowl, means including a diaphragm chamber connecting said tank and float bowl, a diaphragm in said chamber assuming different positions corresponding to different levels, a booster for creating suction in said float bowl, suction operated means for regulating said booster, and suction relieving mechanism for said last mentioned means controlled by said diaphragm.

4. In a fuel lift carburetor of the class described, the combination of a nozzle, a float bowl from which said nozzle is supplied with fuel, a fuel tank from which fuel is sucked to said float bowl, the degree of suction required to draw fuel from the fuel tank to the float bowl being variable, suction operated means for creating suction in said float bowl, other suction operated means for regulating said first mentioned suction operated means, and a third suction operated means for regulating said second suction operated means pursuant to said variable requirements.

5. In a fuel lift carburetor of the class described, the combination of a nozzle, a float bowl for supplying fuel thereto, a fuel tank from which said float bowl is supplied, a booster for creating suction in said float bowl, the degree of suction in said float bowl required to draw fuel from said tank varying with differences in head between said float bowl and the fuel in said tank, a diaphragm chamber interposed between said float bowl and said tank, a diaphragm in said chamber having one surface exposed to the fuel passing

from said tank to said float bowl, a spring for urging said diaphragm in a direction to enlarge said chamber, a pin movable with said diaphragm, a by-pass variably controlled by said pin, and means regulated by said by-pass for varying the degree of suction obtaining in said float bowl.

5 6. In a fuel lift carburetor of the class described, the combination of a nozzle, a float bowl for supplying fuel thereto, said nozzle having a primary air inlet, a mixing chamber into which said nozzle discharges, a secondary air valve for regulating the supply of secondary air to said mixing chamber, a variable chamber beneath said secondary air valve, means for admitting suction to said chamber, a spring for expanding said chamber in opposition to said suction, a booster for creating suction in said float bowl, a pin movable with said air valve to regulate the degree of suction produced by said booster, means for admitting air to said variable chamber to reduce the degree of suction existing therein, a source of fuel for said bowl variable in elevation with respect thereto, and mechanism responsive to said variations in elevation for regulating said air admitting means.

10 7. In a fuel lift carburetor of the class described, the combination of a nozzle, a float bowl constituting a source of fuel supply for said nozzle, a main tank from which said float bowl is supplied with fuel by suction existing in said float bowl, the degree of suction required to draw fuel from said main tank to said float bowl being variable with differences in head between said float bowl and the top of the fuel in said main tank, a booster 15 30 for creating suction in said float bowl, and means controlled by said variation in head for regulating the suction created in said float bowl by said booster.

35 8. In a fuel lift carburetor of the class described,

the combination of a nozzle, a float bowl from which said nozzle is supplied with fuel, a float controlling the admission of fuel to said float bowl, a main tank constituting a source of fuel supply for said float bowl, the head between said float bowl and the top of the fuel in said tank being variable, means for creating suction in said float bowl, and means independent of said float for varying the suction in said float bowl in accordance with said variations in head.

10 9. In a fuel lift carburetor of the class described, the combination of a nozzle, a float bowl from which said nozzle is supplied with fuel, said nozzle having a primary air inlet, a mixing chamber into which said nozzle discharges, a secondary air valve for regulating the supply of secondary air to said mixing chamber, a booster for creating suction in said float bowl, means controlled by said secondary air valve for regulating said booster independently of said nozzle, a fuel supply 15 20 for said float bowl located at variable distances below said float bowl, and means for automatically controlling said secondary air valve in accordance with said variable distances.

10 25 10. In a fuel lift carburetor of the class described, the combination of a fuel chamber, an inlet conduit for said fuel chamber, said conduit connecting said fuel chamber with a fuel supply capable of varying its height with relation to that of said chamber, means for creating suction 30 35 in said fuel chamber to draw fuel thereinto from said fuel supply, means for maintaining the fuel in said fuel chamber between given levels, and means independent of the level of fuel in said fuel chamber for automatically regulating said suction to conform at any given time to the difference in height between said fuel chamber and said fuel supply.

ROBERT F. BRACKE.
